UNITED STATES PATENT OFFICE.

ALFRED T. ANGLE, OF DAYTON, OHIO.

RAIL-BRACE.

1,136,751.

Specification of Letters Patent. Patented Apr. 20, 1915.

Application filed October 15, 1914. Serial No. 866,855.

To all whom it may concern:

Be it known that I, ALFRED T. ANGLE, a citizen of the United States, residing at Dayton, in the county of Montgomery and State of Ohio, have invented certain new and useful Improvements in Rail-Braces; and I do hereby declare the following to be a full, clear, and exact description of the invention, such as will enable others skilled in the art to which it appertains to make and use the same.

My invention relates to improvements in bracing devices for rails and is particularly designed for use at curves, but may be used at any desired point on the track.

The primary object of my invention is to provide a rail brace that comprises a base or supporting member that is constructed similar to a wooden cross tie, and a sectional metallic rail bracing member that is provided at its outer ends with rail clamping members to clamp upon the outer sides of the rail so as to hold them securely against spreading.

Another object is to provide a rail brace of the character described that is of simple construction, may be quickly placed in position without requiring any change in the construction of the track and which is inexpensive to manufacture.

The above and additional objects are accomplished by such means as are illustrated in the accompanying drawings, described in the following specification and then more particularly pointed out in the claim.

With reference to the drawings, wherein I have illustrated the preferred embodiment of my invention as it is reduced to practice, and throughout the several views of which similar reference numerals designate corresponding parts.

Figure 1 is an enlarged detail perspective view of the rail brace. Fig. 2 is a detail plan view of the brace, showing it assembled and applied to a track, and Fig. 3 is a side elevation of my improved device in operative position, showing the rails in section.

Referring to the drawings by characters of reference, the numeral 1 designates as entirely the base or supporting member of my device, which consists of a relatively small cross tie. My improved brace comprises interlocked metallic sections, designated 2 and 3, each of which consists of a rectangular body plate 4 that is of less width

than the tie or base 1 and is formed at its outer ends with an upwardly and inwardly inclined rail clamping jaw 5 which is shaped to conform to and engage the outer face of the base and web of a rail and also the underface of the ball thereof. Each of the plates 4 is provided with relatively thin longitudinal flanges 6 on the longitudinal edges thereof. The flanges 6 extend for a distance equivalent to approximately half the length of the plates from the outer end thereof to a point approximately centrally of the ends of the plates. The outer half of each plate or a distance equivalent to the length of the flanges 6 approximately, is raised upwardly or enlarged to provide a rail supporting surface 8. The flanges 6, in being relatively thin, enables the overlapping of the heads of spikes thereupon, and the secure fastening of the brace upon the supporting base 1 therefor.

Formed on the inner end of the plate 4 of the section 2 is an upstanding transverse lug 9 that extends the entire width of the section irrespective of the flanges 6.

Formed on the corresponding end of the plate 4 of the section 3 in an inverted and approximately U-shaped hook 10 which has the side arm portion that is free formed shorter than the secured side arm portion which is formed integral with the plate so that the bottom faces of the plates of the sections may be disposed flush with one another. The lug 9 extends within the hook 10 and fits snugly therein. A right angularly extending flange 11 is formed integral with the lower edge of the free end of the hook 10 and is provided with a central aperture 12. This flange 11 is disposed in a horizontal plane and arranged to engage the upper face of the plate 4 of the section 2, when the sections are in interlocked position, as shown clearly in Fig. 3. An aperture 13 is provided in the plate 4 of the section 2 and arranged to align with the aperture 12 in the flange 11. A pin, bolt or other suitable fastening element or a spike 14 is inserted through the aligned apertures 12 and 13 and driven into the base or support 1.

In the outer face of each of the rail clamping members 5, a recess 15 is formed. The recess 15 extends down through the end of the plate 4 and is so shaped as to receive the head of a spike to be driven into the rail.

porting tie 1. Spikes 16 and 17 are arranged on opposite sides of the device and engage the sections 2 and 3 respectively at a point intermediate the ends thereof with 5 their heads.

With reference to the foregoing description and accompanying drawings, it will be observed that I have provided a rail brace which will securely hold rails against 10 spreading and which is simple in construction and capable of being readily attached at a curve or desired place along the track without requiring change in the construction of the track or roadbed and use of 15 skilled labor. My improved device may be readily taken down for shipment and stored in comparatively small space.

In practice I have found that the form of 20 my invention, illustrated in the drawings and referred to in the above description, as the preferred embodiment, is the most efficient and practical; yet realizing that the conditions concurrent with the adoption of 25 my device will necessarily vary, I desire to emphasize the fact that various minor changes in details of construction, proportion and arrangement of parts may be resorted to, when required, without sacrificing

any of the advantages of my invention, as set forth.

What is claimed is:—

A rail brace comprising interlocked sections, each consisting of an elongated plate, rail clamping members formed on the outer ends of said plates, an inverted U-shaped hook 35 formed on the inner end of one of said plates and having its free arm portion formed shorter than the integral arm portion, a laterally extending flange formed integral with the free arm portion of the lower end thereof and having an aperture therein, an upstanding lug formed on the corresponding end of the plate of the other section, an aperture formed in the plate of said last named section and arranged to align with an aperture in said last named flange, said lug arranged to extend within said hook, said flange to engage upon the face of the last named section, and a fastening element inserted through the aligned apertures.

In testimony whereof I affix my signature in presence of two witnesses.

ALFRED T. ANGLE.
